JOHN C. HULL, OF GASPORT, NEW YORK

SPRAY GUN

Application filed February 18, 1927. Serial No. 169,351.

This invention relates to a spray gun construction and more particularly to the nozzle portion of such a construction.

The primary object of the invention is to provide a nozzle structure of sturdy design and construction and which will afford an accurate and minute control of both the quantity and character of a stream of fluid to be projected therethrough.

10 Further objects relate to the arrangement and relative disposition of the parts affording convenient assembly and disassembly and ready access for purposes of inspection, repair or replacement.

15 Other objects and advantages of the invention will appear in connection with the following detailed description of the specific structural embodiment chosen for illustration in the drawings.

20 Figure 1 is a longitudinal section through a spray gun embodying my invention.

Figure 2 is a vertical section taken on line 2—2 of Figure 1.

25 Figure 3 is a vertical section taken on line 3—3 of Figure 1, and

Figure 4 is a vertical section on line 4—4 of Figure 1.

The nozzle structure in which my invention is incorporated may be employed with 30 any suitable form of pressure chamber, such for example as the pressure cylinder 1 as shown in the drawings. The nozzle may have a threaded connection with the end of the pressure cylinder or may be welded or otherwise secured thereto as desired. The nozzle body indicated at 2 in the drawings is in the present form of the invention shown as being of elbow formation. Certain advantages arise by reason of the discharge end 35 of the nozzle body extending at an angle to the longitudinal axis of the spray gun, such for example as convenience in the manipulation and use of such a gun in close quarters.

40 The discharge end of the nozzle body 2 is provided with a cap 3 having a conical discharge chamber 5 and a discharge port 4 registering with the said chamber.

45 My improved valve mechanism which is disposed within the nozzle body comprises a 50 valve body 6 provided with external screw

threads 7. Cooperating with the threads 7 of the valve body is a corresponding set of internal threads 8 provided on the inner surface of the nozzle body. It is thus apparent that a rotary movement of the valve body 51 by means of the valve stem 9 effects a longitudinal movement of the valve body in opposite directions depending upon the direction of rotation of the valve stem. Formed integrally with the valve body is a reduced 60 valve portion 11 which is adapted to cooperate with the adjacent end of a tubular elbow member 12 fitted within the outer end of the nozzle body. The tubular valve member is formed as is clearly shown to correspond with 65 the angularity of the two portions of the nozzle body. This tubular valve member is provided with a disk portion at one end having a plurality of apertures 13 disposed therein. The valve body 6 is provided with a plurality 70 of longitudinally disposed grooves 15 passing through and interrupting the threads 7 on its periphery. The valve body 6 also has formed thereon a conical portion 6' adapted 75 to cooperate with a valve seat 14, which seat is in the form of a ring forced or otherwise secured within the body 2.

From the foregoing description of the structure of my invention it should be apparent that the compressed fluid within the pressure chamber 1 has at all times a free passage through the longitudinal passageways 15 in the valve body 6 into the vicinity of the adjustable valve mechanisms. The fluid so passing through the passages 15 may reach 80 the discharge port 14 of the nozzle cap by either of two different paths. A variable flow of fluid may be by-passed around the elbow member 12, thru apertures 13 and into 85 the conical discharge chamber 5, by suitably adjusting the valve stem 9 and effecting thereby a variable opening or closing of valve members 6' and 14. Fluid may also pass in varying 90 quantities through the tubular valve element 12 and into the conical discharge chamber 5 depending upon the position of the valve member 11.

95 A nozzle constructed as described above affords a very accurate control of both the 100 quantity and character of fluid to be pro-

jected therethrough by reason of the two separate and variable passages for the fluid. It is apparent that if the valve members 11 and 12 be in close position the fluid can pass only around the tubular valve member 12 through valve 6', and apertures 13. If, however, the valve member 11 is adjusted to permit passage of fluids through the tubular valve element 12, it is apparent that the character of the stream passing around member 12 will be modified in proportion to the extent of opening of the valve. By imposing this variable flow of fluid under pressure upon the first mentioned variable flow it is possible to obtain a very wide range of changes in the character and quantity of the stream projected.

I desire to emphasize the importance of the two simultaneously adjustable, but independent feeds which characterize my improved nozzle construction. The fluid passed thru valve member 14 as controlled by the supplemental conical valve member 6' assumes a rotational or swirling condition in the 25 conical discharge chamber 5, by virtue of it passing between the threads 7 and 8 of different depths. The feed governed by valve member 11 and passing thru elbow member 12 is a center feed as distinguished from the 30 circumferential feed around the elbow member. The center feed serves to confuse the rotating or swirling fluid of the circumferential feed and thus affords a discharge of widely 35 variable characteristics. It will be observed that the movement of valve body 6 rearwardly of the nozzle effects first a variable separation of valve members 6' and 14 while maintaining valve members 11, 12 in closed position. This adjustment produces the variable 40 circumferential feed, but upon continued rearward movement of the valve body, the valve members 11, 12 are opened thus imposing the variable direct center feed upon the circumferential feed. It is, of course, apparent 45 that a complete shut-off is obtained by screwing the valve body to its extreme forward position.

The arrangement of the parts comprising the present embodiment of my invention is such as to afford a convenient assembly and disassembly of parts. The valve body 6 is pinned to the valve stem 9 and may be readily removed therewith longitudinally of the spray gun. By removing the threaded discharge cap 3 access may be had to the tubular valve element 12 which may then be readily removed and repaired or replaced. These parts constitute the spray gun nozzle and it is apparent that there is little likelihood of failure by reason of breakage or displacement of the parts.

It should be clearly understood that different forms of nozzle caps can be interchangeably employed in place of the cap 3 as herein shown. For example, I may employ a con-

ventional cap containing a flat apertured detachable disk and gasket, when the gun is to be employed for orchard work and the like.

While I have shown but a single specific embodiment of my invention I do not wish to be understood as limiting invention to all the structural details of such embodiment but intend that many of the details may be modified in various ways without departing from the spirit of the invention as defined in the appended claims.

What I claim is:

1. In a spray gun, the combination with a pressure chamber, a nozzle body secured thereto, a rotatable valve spindle disposed within said pressure chamber and extending into said nozzle body, an externally screw-threaded valve member secured to said spindle, a valve seat therefor, screw threads on the interior of said nozzle body and coacting with the threads on the valve member, said valve member having a plurality of longitudinally disposed slots formed in the surface thereof and of a depth greater than that of said screw threads, a cap secured to the outer end of said nozzle body and having a discharge aperture therein, a tubular conduit disposed intermediate said cap and valve body and communicating with said discharge aperture and forming with said nozzle body a by-pass around said conduit which is also in communication with said discharge aperture, and means formed on said valve body for controlling the flow of fluid through said conduit and by-pass, said valve member arranged to engage said conduit in advance of its engagement with said valve seat.

2. In a spray gun, the combination with a pressure chamber, a nozzle body secured thereto, a rotatable valve spindle disposed within said pressure chamber and extending into said nozzle body, an externally screw-threaded valve member secured to said spindle, screw threads on the interior of said nozzle body and coacting with the threads on the valve member, said valve member having a plurality of longitudinally disposed slots formed in the surface thereof and of a depth greater than that of said screw threads, a cap secured to the outer end of said nozzle body and having a discharge aperture therein, a tubular conduit disposed intermediate said cap and valve body and in spaced relation to the inner annular wall of said nozzle body whereby to form a by-pass around said conduit, a member secured in said nozzle body intermediate the conduit and valve member and having a valve seat opening in communication with said by-pass, and means formed on said valve member and adapted to coact with said conduit and with said valve seat for controlling the flow of fluid through said conduit and by-pass, said valve member arranged to engage said conduit in advance of its engagement with said valve seat.

130

3. In a spray gun, the combination with a pressure chamber, a nozzle body secured thereto, a rotatable spindle disposed within said pressure chamber and extending into said nozzle body, an externally threaded valve member secured to said spindle, a cap secured to the outer end of said nozzle body and having a discharge aperture therein, a tubular conduit disposed intermediate said cap and valve body and in spaced relation to the inner annular wall of said nozzle body whereby to form a by-pass around said conduit, a member secured in said nozzle body intermediate the conduit and valve member and having a valve seat opening in communication with said by-pass, said valve member having a conical portion and a cylindrical portion for coaction with said valve seat and conduit respectively for controlling the flow of fluid therethrough, said valve member arranged to engage said conduit in advance of its engagement with said valve seat.

4. In a spray gun, the combination with a pressure chamber, a nozzle body secured thereto, a rotatable spindle disposed within said pressure chamber and extending into said nozzle body, an externally threaded valve member secured to said spindle, a cap secured to the outer end of said nozzle body and having a discharge aperture therein, a tubular conduit disposed intermediate said cap and valve body and in spaced relation to the inner annular wall of said nozzle body whereby to form a by-pass around said conduit, a member secured in said nozzle body intermediate the conduit and valve member and having a valve seat opening in communication with said by-pass, said valve member having an end portion of substantially cylindrical form for coaction with said conduit and an intermediate portion of substantially conical form for coaction with said valve seat, said valve member arranged to engage said conduit in advance of its engagement with said valve seat.

5. A nozzle comprising a hollow body of elbow form, an apertured cap secured to the end of said body, a tubular conduit of elbow form disposed within said body adjacent said cap and being of less external diameter than the bore of said hollow body to provide a by-pass around said conduit, a valve seat formed in said body inwardly of the inner end of said conduit and a valve member having surfaces for coaction with said valve seat and conduit to seal the same, said valve member arranged to engage said conduit in advance of its engagement with said valve seat.

60 In testimony whereof I affix my signature.
JOHN C. HULL.
